UNITED STATES PATENT OFFICE

WILBUR N. SQUIRES, OF JOPLIN, MISSOURI, ASSIGNOR TO HYDRAULIC DEEP WELL PUMP COMPANY, OF JOPLIN, MISSOURI, A CORPORATION OF MISSOURI

HYDRAULIC PUMP

Application filed May 5, 1928. Serial No. 275,404.

My invention relates to deep well pumping systems of the type employing a pumping mechanism disposed within the well and actuated through hydraulic connections by a jack or operating connections at the head of the well.

In pumping systems of this class, as heretofore known, there have been two types. The first type employs a source of unidirectional fluid pressure supplied as by a pump at the head of the well and a motor mechanism forming a part of the pump within the well and having a piston member driven alternately in one direction and then the other through the intervention of a switching valve mechanism. If the switching valve is placed at the head of the well it is subjected to the excessive hydraulic pressure, and the life of such a valve is usually very short. If the switching valve is disposed within the well, it must be designed to go into a restricted space, is inaccessible and is likely to stop on dead center from which it is difficult to move it.

A second type of system involves the use of alternately pulsating columns of liquid on opposite sides of a pump actuating piston or motor piston. These columns are preferably actuated by the pistons of the pulsator at the end of the well. In my prior applications, Serial No. 158,896 and 219,922, I have disclosed and claimed pumping systems of the second type.

The present invention relates to a system differing from both of the above types in the essential feature of having one stroke of the motor mechanism that operates the pump made by the static pressure head of both columns against an external pressure, for example, that obtaining in the well where the pump is disposed.

I supply pulsating or periodic unidirectional pressure in one hydraulic line only and employ a switching valve which opens under pressure to equalize the pressure between the two lines, and closes when the return stroke has been completed by the static pressure head, that is, when the pressures upon both sides of the switching valve are equalized or substantially equalized.

I employ two concentric hydraulic lines, the inner one of which preferably is the power line, and the outer one of which is preferably the discharge line, although this may be varied at will. The piston which operates the pump in the well is subjected on one side to the pressure within the power line and on the other side to the pressure within the discharge line.

When a pressure stroke is made by the said piston as, for example, by means of a single cylinder pump jack, the piston is moved in one direction to the end of its stroke, whereupon a switching valve is opened to equalize the pressure upon both sides of the piston, and movement of the piston on the return stroke is made by a connected differential piston which on one side has the static pressure of the two hydraulic columns and on the other an inferior pressure such as atmospheric or a suitable low pressure such as may prevail in the well in which the pump is located. The preponderance of static pressure over such low pressure is able to make the return stroke of the power piston and to close the switching valve so as to separate the two columns to permit the next power stroke to be made.

The specific arrangement of motor piston and differential static piston may be widely varied within the scope of my invention. I believe it is broadly new to employ the difference between the static pressure and a suitable low pressure such as atmospheric or the submergence pressure in the well to make the return stroke of the motor piston. It can be seen that all of the power which is employed in raising the liquid from the well must come from the jack or pulsator mechanism at the head of the well, and each stroke of the pulsator provides power for two different actions, that it to say, on the power stroke of the motor piston, liquid is discharged from the well, and at the same time power is stored in the pumping mechanism to make the necessary return stroke of the motor piston.

Now in order to acquaint those skilled in the art with the manner of constructing and operating a device embodying my invention, I

shall describe in connection with the accompanying drawings a specific embodiment of the invention.

In the drawings:

5 Fig. 1 is a diagram showing the relation of the two static columns, the piston between them, the valve controlling the connection of the two columns, and the differential piston by which the return stroke is capable of being made.

10 Fig. 2 is a similar diagram, illustrating the manner in which the operating mechanism of Fig. 1 may be employed in the pumping of liquid.

15 Fig. 3 is a similar diagram showing a modification in which the pumping stroke is made by the static plunger.

Fig. 4 is a diagram more in detail of a system embodying my invention.

20 Fig. 5 is a longitudinal vertical section through the upper end of a pump embodying my invention.

Fig. 6 is a section taken on the line 6—6 of Fig. 5.

25 Fig. 7 is a section taken on the line 7—7 of Fig. 5.

Fig. 8 is a fragmentary section taken on the line 8—8 of Fig. 7.

30 Fig. 9 is an end view of the parts shown in Fig. 8.

Fig. 10 is a section taken on the line 10—10 of Fig. 5.

35 Fig. 11 is a longitudinal section taken through the lower end of the pump shown in Fig. 5 but at right angles to the section taken at Fig. 5 showing also the intake valve construction.

40 Fig. 12 comprising two separate views, part I and part II, of which part II is to form a continuation of the lower end of part I, shows a longitudinal vertical section through a modified form of pump of my invention.

Fig. 13 is a cross section taken on the line 13—13 of Fig. 12.

45 Fig. 14 is a vertical section taken on the line 14—14 of Fig. 13.

Fig. 15 is a cross section taken on the line 15—15 of Fig. 12.

50 Fig. 16 is a fragmentary longitudinal section taken on the line 16—16 of Fig. 12.

Fig. 17 is an end view of the part shown in Fig. 16.

Fig. 18 is a cross section taken on the line 18—18 of Fig. 12.

55 Fig. 19 comprising part I, part II and part III, which are adapted to be placed end to end with part I at the top, is a longitudinal vertical section of a modified form of pump.

60 Fig. 20 is a fragmentary section taken at right angles to Fig. 19.

Fig. 21 is a section taken on the line 21—21 of Fig. 19.

65 Fig. 22 is a section taken on the line 22—22 of Fig. 19.

Fig. 23 is a section taken on the line 23—23 of Fig. 19.

Fig. 24 is a fragmentary detail view of the spring pressure plate.

Referring now to Fig. 1, assume that two hydraulic columns, 1 and 2, are separated by a movable piston 3 in a cylinder member 4, and that a differential stem or piston 5 projects out through a wall of the cylinder 4 so that its cross sectional area is exposed to 75 atmosphere.

The piston 3 has an aperture 6 therethrough which is adapted to be controlled by a valve 7, which valve 7 is shown diagrammatically only. Assume that the valve 7 is closed and the parts are in the position shown, and that pressure is applied to the column 1 driving the piston 3 to the left as viewed in Fig. 1, the valve 7 being at this time closed. Assume that when the piston 3 reaches the end of its stroke towards the left, the valve 7 is open and remains open until the piston 3 is moved completely to the right. It will be seen that the static pressure of liquid in both columns 1 and 2 will be equalized upon opposite sides of the piston 3 so that there is no difference of pressure tending to move the same. However, the static head of both columns is equalized and is exerted on the cross sectional area of the stem 5 tending to drive it 90 to the right. When the piston 3 is driven to the end of its stroke or to the right, as viewed in Fig. 1, the valve 7 is again closed, whereupon another impulse of pressure may be applied to the column 1 and another cycle 95 of operations will occur.

It can now be seen that by this mode of operation the application of pressure to the piston 3 to move it to the left need not be carefully metered since the opening of the 1 valve 7 when the piston arrives at the limit of its travel toward the left permits any excess of displacement of the pulsator plunger 8 in pulsator cylinder 9 to be freely discharged into the column 2. Upon the return stroke of the pulsator piston 8 the only force effective to move the piston 3 is the static head operating on the cross section of the plunger 5.

From the diagram of Fig. 1 it will be appreciated that it is possible through a differential piston arrangement to permit the pulsator to drive the motor piston 3 through a complete stroke even though the displacements of the pistons 8 and 3 are not exactly correlated.

In the building of pumps of the character referred to in my prior applications it was found that the yield of the containing pipes and other parts is such as to make the correlation of piston displacement and motor displacement very difficult, but by the scheme here outlined that difficulty is now obviated.

The diagram of Fig. 1 of course does not show any utilization of the motion of the

motor piston 3, but this may be done in a variety of ways and with a variety of apparatus. For example, in Fig. 2 I have shown the differential plunger 5 as connected to a pump plunger 10 operating in a cylinder 11, which cylinder through the medium of intake and discharge check valves 12 and 13 is operative to draw liquid from the well and discharge the same into the discharge column 2 upon the power stroke of the motor piston 3. I have shown the differential plunger 5 as connected to the pump plunger 10 by connection 14, which may be of any suitable character. The pumping cylinder 11 discharges into the discharge column 2 either through the end of the cylinder 4 or otherwise. The operation of the system diagrammatically shown in Fig. 2 is as follows:

Assume that the pulsator piston 8 is operated to discharge liquid into the power column 1. The valve 7 is closed. The application of pressure to the column 1 and the right hand side of the motor piston 3 causes the motor piston 3, the differential plunger 5 and the pump plunger 10 to move to the left as viewed in Fig. 2. To make a complete stroke, at the end of the stroke, the valve 7 is opened and remains open until the piston 3 is moved completely to the right, as viewed in Fig. 2. The movement of the piston 3 and plunger 10 to the left has caused a discharge of liquid from both the left hand side of the cylinder 4 and from the pump cylinder 11 through the discharge pipe 2. When the valve 7 is opened at the end of the stroke, the pressures upon opposite sides of the piston 3 and cylinder 4 are equalized and remain so throughout the return stroke. The check valve 13 prevents any pressure being applied to the pump plunger 10, but a static pressure is applied to the differential plunger 5, and the differential plunger 5 is of a cross sectional area greater than the cross sectional area of the plunger 10 to the end that the plunger 5 is able to move the plunger 10 to the right to make a suction stroke of the pump cylinder 11. Depending upon the differences in pressure, the relation of the areas of the pistons 5 and 10 may be widely varied.

It will be observed that the return motion, which is made by the preponderance of static pressure over the submergence pressure in the well, performs the suction stroke of the pump cylinder 11.

If desired the reverse relation may be employed, namely, that the power stroke of the piston 3 may make the suction stroke of the pump and the discharge stroke of the pump cylinder may be made by the application of static pressure to the differential plunger. For example, I have shown in Fig. 3 the manner in which this may be done. In this case the pumping cylinder 11 having its inlet and discharge valves 12 and 13, is adapted to have the operating plunger 10

connected directly in line with the differential piston 5' which is made of a diameter greater than the diameter of the pumping plunger 10, so that upon the completion of a stroke to the left and opening of the valve 7 the static head operating on the cross section of the plunger 5' is great enough to cause the pumping plunger 10 to be driven to the right in the cylinder 11 to discharge the contents of the cylinder 11 into the discharge column 2. At the same time the pumping plunger 3 is returned to the right and the valve closed. In the system shown in Fig. 4 I have shown diagrammatically but more in detail a system in which the static head is employed for making the return stroke of the power plunger when the switching valve is open to equalize the pressures between the two columns. The diagram of Fig. 4 is structurally an exposition of the modification shown in Figs. 5 to 11.

In Fig. 4 the pulsator 15 is shown as having a plunger 8 moving in a cylinder 9 corresponding to the diagrams of Figs. 1 to 3.

The cylinder 9 has a sleeve 16 movable by ring friction to open and close a port for the admission of liquid from a supply pipe 17 and intake chamber 18 to discharge the same through the pipe 19 down through the column 1 to the interior of cylinder 4 and upon the upper side of the hollow piston 3. The sleeve valve 16 has an inturned flange member 20 and a square or flat face thereon which is adapted to engage the internal flat face of the head 21. When the plunger 8 is drawn to the right, as viewed in Fig. 4, the friction of the piston rings 22 causes the sleeve valve 16 to be moved endwise to abut against the stops 23 to provide a separation of the flange 20 from the head 21 so that the cylinder may be filled with liquid to be discharged into the column 1. Upon the beginning of the power stroke the ring friction seizes the sleeve valve 16 and moves it into contact with the head 21. The pressure within the cylinder acting upon the flange 20 holds said valve in tightly closed position so that the discharge stroke may be made.

The motor piston 3 comprises a hollow tubular member having an enlargement 24 at its lower end enclosing a rotary valve 25 having ports 26 adapted to be brought into register with similar ports 27 in the side walls of the enlargement 24. The valve 25 has an operating arm 28 on which there is mounted a roller 29 and the arm 28 moves through an arcuate opening or slot so as to shift the valve 25 from open to closed position and vice versa. At the end of the downward stroke the roller 29 engages an inclined cam or track 30, which shifts the valve 25 to open position, as shown in Fig. 4.

On the return stroke the roller 29 engages a cam or track 31 inclined in the same direc-

tion and adapted to shift the valve 25 to closed position. The motor piston 3 is connected to a hollow pumping plunger 10 as by means of a stem 32 and valve cage 33 enclosing the discharge check valve 13. A cylinder member 11 houses the pumping plunger 10, and it communicates by way of a pipe 34 and intake check valve 12 with the source of liquid to be pumped. The hollow pumping plunger 10 at its lower end is connected through a spider 35 and stem 36 to a differential piston 5 moving in the differential cylinder 37. One side of the piston 5 is exposed to atmospheric pressure or submergent pressure in the well, whereas the opposite side, namely, in the cylinder 37, is exposed to static pressure within the column 2, and when the valve 7 is open, the pressure of the two columns is substantially equalized upon the opposite ends of the plunger 5, as viewed in Fig. 4. The communicating passageway 38 provides a connection between the lower end of the column 2 and the interior of the cylinder 37. The column 2 is provided on the outside of the column 1 concentric therewith, and at its upper end has a discharge connection 39 leading to a suitable receiver or reservoir 40 into which the liquid is pumped.

The operation of this system is as follows: Assume that the pulsator piston 9 has just completed its power stroke to the left as viewed in Fig. 4, and the motor piston 3 with its connected parts has been driven down to a point where the valve 7 has been opened and pressure equalized. The delivery of any further pressure at the end of the stroke of the pulsator piston merely discharges liquid freely through the ports 26, 27. The valves 13 and 12 are at this time on their seats. Since the upper part of differential plunger 5 is exposed to a greatly inferior pressure and the lower part of the cylinder 37 is exposed to the full static pressure of the columns 1 and 2, and since the area of plunger 5 is greater than the cross sectional area of the plunger 10 in the cylinder 11, it can be seen that the system of movable parts will travel upwardly. As the valve 7 is open, the motor piston 3 can travel upwardly freely with no resistance other than the friction of the piston 3 in the cylinder 4. The upward motion of the pumping plunger 10 creates a displacement of liquid in the lower part of the column 2 against the full static pressure therein since the check valve 13 must remain seated. Thereby the net result of the upward motion of the plungers 10 and 5 is a displacement outwardly of a part of the liquid under full static head. The upward motion of the pumping plunger 10 draws liquid into the cylinder 11 through the inlet check valve 12. When the system has moved to the limit of its upward stroke or approximately so, the roller 29 on the arm

28 engages the cam track 31, which shifts the valve 7 to closed position.

Thereupon the two columns are cut off from each other and the piston 3 again becomes operative to make a power stroke. As the motion of the pulsator plunger 8 begins towards the left to make the power stroke the sleeve valve 16 is closed, and the liquid contained within the cylinder 9 is forced down through the column 1 and acts upon the cross sectional area of the piston 3 within the cylinder 4. Thereupon the piston moves downwardly. The valve 13 is immediately opened, and the liquid which had previously been drawn into the cylinder 11 is now displaced into the column 2 past the check valve 13, the inlet check valve 12 at this time remaining closed and sustaining the full pressure of the static column.

The real pumping, that is, displacement of the liquid from the column 2, occurs on the down stroke of the piston 3 and plungers 10 and 5 both by virtue of the movement of the piston 3 in cylinder 4, displacing liquid in the column 2 by its movement, but more particularly by displacement of liquid by plunger 5 in cylinder 37. To whatever extent movement of the hollow plunger 10 in cylinder 11 displaces liquid therefrom, this is added to the displaced liquid in column 2, causing it to discharge into the receptacle 40. The upward or return stroke has a differential displacing effect, namely, that of the plunger 10 and the plunger 5, the net result of which is a net drop of the column 2.

Referring now to Figs. 5 to 18 in which I have shown the details of structure of pump and cylinders 4 and 11, which are shown diagrammatically in Fig. 4, it will be seen that I have constructed the pump in a form which will adapt it to be disposed in a well.

The pump shown in Fig. 5 comprises a number of sections, the upper section 41 enclosing the cylinder 4. The next section 42 is a section of seamless tubing of thin walls suitably enclosing the enlarged end 24 of the plunger 3 and the upper end of the pumping plunger 10. The next structural section comprises a piece of seamless tubing 43 enclosing a block 44 forming the cylinder 11 for the pumping plunger 10. Below this there is another section of tubing 45 to provide space within which the differential plunger 5 may operate, and below the section 45 is a further section 46 enclosing a block or forging 47 containing the differential cylinder 37. Below this section 46 is a coupling 47 for holding the cylinder head member 48 and for connecting the intake check valve cage 49. A further section 50 providing a screen and footing forms the bottom of the pump.

These sections are all coupled together by screw threads, as will be apparent from the drawings. The cylinder member 4, as can be seen in section in Fig. 6, provides a plural-

ity of passageways 51, 51 formed by longitudinal grooves or flutes, these flutes forming part of a connection between the outer pipe defining the column 2 and the inner pipe defining the column 1. Longitudinal ridges or lands 52 fit closely within the walls of the coupling 41, being forced thereinto by hydraulic pressure and the like to cause the coupling 41 to embrace the cylinder member 4. The hollow plunger 3 is adapted to move within the bore of the cylinder member 4, and this piston member 3 has an enlarged head 53 onto which there is threaded a valve cage member 54 enclosing the rotary valve 7. The cage member 54 is provided with ball bearings 55 for mounting the rotary valve 7, said valve having a stem 56 extending down through the thrust bearing 55 and having a suitable head 57 to hold the valve in place. The registering ports 26, 27 are clearly shown in section in Fig. 7, and the operating arm 28 which bears the roller 29 is also shown in Fig. 7. The cam members 31 and 30 are shown in Figs. 8 and 9, and the path of the roller 29 is indicated by dotted lines and arrows. As shown in Fig. 5, the piston is in its uppermost position when the valve 7 is closed. The head 54 may be provided with guiding wings 58 embracing a track 59 as shown in Fig. 7, although as will be apparent from the drawings, the guides of the head 54 may be imposed upon the rods 60 which connect the head member 54 with the head 61 of the differential piston 5. These rods 60, 60 are connected at their upper ends to the head member 54 of the power piston 3 and at their lower ends to the head member 61 to which there is secured the tubular differential plunger 5. The rods 60, 60 pass down through the block 44 which forms the pumping cylinder 11. This block in addition to containing the rods 60, 60 has passageways 63, 64 extending longitudinally through the same on opposite sides of the cylinder 11 for the passage of liquid through one of them and to the cylinder 37. These passageways are shown in Figure 11. One of the passageways 64, in the member 44, continues on through the block 65, thence through the member 66, the cylinder block 47, and communicates with the bottom of the cylinder 37 of the differential plunger 5. This passageway 64, as constructed in the device of Figures 5 to 11, corresponds to the passageway 38, shown in the diagram of Figure 4.

The cylinder block 44 houses, at its lower end, a valve cage 67 for the primary inlet check valve 12, a secondary inlet check valve 68 being employed at a lower level in cage 49. The piston member 10 which moves within the cylinder 11 is connected, at its upper end, through the cage member 33 and a short stud 32 to the head 54 of the power piston 3. The upper check valve 12 may be omitted in favor of the single main check valve 68, as has been shown in Figure 5. The intake passageway below the check valve 12 is provided by an offset passageway 71 in the member 66, as shown in Figures 10 and 11. The central part 70 of the block 66 is arranged to provide a space in which the head 61 of the differential plunger 5 may operate freely. The differential plunger 5 is a hollow tubular member, fitting closely in the bore 37. The passageway 71 in 75 the member 66 registers with a similar passageway in the cylinder block 47. The head member 48, which is a separate block fastened endwise in alignment with the cylinder block 47, has an offset passageway 72 extending to 80 the central part of the cage member 49 and held in place by the coupling 47.

The footing and screen member 50 is welded onto a coupling member 73, which in turn, is threaded to the lower end of the 85 cage member 49. A suction pipe 74 is connected to the cage 49 through the intermediary of the coupling member 75, threaded externally and internally, as shown in Figure 11. The space in which the upper end of the plunger 5 and its head member 61 play is closed off from communication with either of the columns 1 or 2 and is open to atmospheric or submergence pressure, if preferred, 95 but I have shown a passageway 76 communicating with the space 77, in which the plunger 5 plays and leading through a small check valve 78 to the outside of the casing. Thus, any fluid which tends to collect in the 100 space 77 may be expelled and the entry of foreign matter to said space 77 is prevented by the check valve 78, any suction which may be created in said space 77 because of the presence of said check valve 78 being 105 immaterial to the operation of the device and having no appreciable retarding effect upon the movement of the parts.

It can now be seen that the mechanical assembly shown in Figures 5 to 11 is diagrammatically illustrated in Figure 4 and the operation of the parts shown in Figures 5 to 11 is identical with that disclosed in said Figure 4.

The rods 60—60 fit close enough in the 115 bores which pass through the cylinder member 44 and cylinder head block 65, to prevent any appreciable leakage from the outer column 2 to the free space 77. The various parts are held in endwise alignment by the 120 threaded connections above described.

Mounting of the valve 7 on roller bearings provides for a minimum of friction between the parts, since the major part of the pressure is downward and the pressure upon 125 the walls of the valve 7 is substantially balanced. Obviously, the parts may be arranged in a different manner, that is, the various pistons, plungers, and operating 130 connections, and I have shown a modified

form of arrangement in Figures 12 to 18, inclusive. In this form of device, the inner column 1 is shown as communicating through a coupling member 80, head member 81, and cylinder member 82, to the upper end 5 of the operating piston 3 in the cylinder block 83. In this case, the differential plunger 84 is mounted in a bore 85 in the cylinder member 82 above the power piston 3. The coupling member 80 and the head member 81 are held together and in register by a threaded seamless tubing member 86, which is threaded to the top of the cylinder member 82. A head member 81 10 which forms a spacing block is set against a shoulder in the cylinder member 82 and is held in place by a downwardly extending tubular portion 88 which surrounds the block and is threaded to the top of a cylinder block 83. The cylinder block 83, at its lower end, in turn, is threaded to a tubular coupling 89, which, at its lower end, supports a spider member 90 above the upper end 20 of a cylinder member 91, a second coupling member 92 extending from the lower end of the coupling member 89 to the lower end of the cylinder block 91.

A flanged coupling member 94 forces the cage 95 against the lower end of the cylinder block 91. A passageway 96 extends from the center of the coupling member 80 30 downwardly into communication with a continuation 97, formed longitudinally in the cylinder block 82. This communicates laterally, at 98, with a central part of the block or head 81 and the bore of the cylinder block 83 in which the power piston 3 moves. The differential plunger 84 is connected by a rod 99 and coupling member 100 with the 40 top of the power piston 3, so that the two parts mechanically are unitary.

The column 2, which is the outer column, communicates by a passageway 101 which extends successively through the coupling member 80, head member 81, cylinder member 82, head member 87, power cylinder member 83, down to the space 102 in which the lower end of the power piston 3 and the upper end of the pumping plunger 10 are 45 disposed to move. The enlarged head 53 of the power piston 3 carries the cage 54 which forms, when the valve 7 is closed, the actual head of the piston 3. The rotary valve 7 is mounted on a thrust ball bearing 55, provided with a stem 56 and this stem, in turn, is connected to an operating arm 28 bearing a roller 29 for engagement with the cams or tracks 31 and 30, at the upper and lower ends of its travel, respectively. The head 60 member 54 has a laterally extending slide 58 adapted to be guided by a track 59 to prevent rotation of the movable system when the arm 28 engages the cams 30 or 31. A valve cage 33 containing the discharge check 65 valve 13 connects the lower end of the power

piston head 54 with the top of the pumping plunger 10.

The pumping plunger 10 plays in the bore 37, the lower end of which communicates with the inlet check valve 12, which is 70 mounted in a suitable cage 104. The spider member 90 is shown in section in Figure 18. It is provided with openings, such as 105, to permit scale and the like, which may settle out of the oil when the pump is first started, 75 to be received in an annular pocket 106 surrounding the pumping cylinder 37. It is often the case that, in assembling a pump of this character, a certain amount of sand and scale unavoidably becomes enclosed within the pump and unless provision is made for disposing of the same after the pump is in place, it will lodge in such position with respect to the movable parts, particularly the pumping cylinder as to cause it to wear out 80 or wear loose rapidly. This is prevented by the sharp formation of the upper end of the cylinder block 91 and arrangement to trap scale, sand and the like in the pocket 106.

The upper end of the differential cylinder bore above the plunger 84 communicates with the outside of the pump through a check valve 107, shown in dotted lines in Figures 12 and 13, to permit the same to 85 eject any fluid which might leak into the same.

The operation of the system thus far shown is substantially the same as heretofore described in connection with Figure 4, the difference between the device of Figure 12 100 and Figure 4 being largely a matter of mechanical arrangement. The upper end of the differential piston 84, in this case, is exposed to atmospheric or submergence pressure. 105

The valve 107 may be omitted. The lower side of the differential piston 84 communicates with the power column 1 at all times. Likewise, the upper side of the power piston 3 communicates, at all times, with the power column 1. The lower side of the power piston 3 communicates at all times with the column 2 through the passageway 101. The two columns are put into free communication when the power piston 3 is 110 driven to the bottom of its stroke and they are disconnected by closing of the valve 7 when the power piston 3 and connected parts are moved to the upper end or top of their stroke. The top of the pumping piston 10 is, 115 at all times, in communication with the column 2 and the bottom of the said pumping plunger 10 is, at all times, in communication with the intake passageway 108, through the check valve 12. When the parts are in 120 the position shown, the valve 7 is closed, and pressure is applied to the top of the power piston 3 and the bottom of the differential plunger 84. Since the area of the power piston 3 is greater than the area of the dif- 125 130

5 differential piston 84, the power piston 3 moves downwardly to the end of its stroke. In doing so, it drives the pumping plunger 10 downwardly, opening the valve 13 and causing the transfer of liquid from the pumping cylinder 37 to the space 102. At the end of the stroke, the valve 7 is shifted to permit the columns 1 and 2 to communicate with each other and equalize the static pressure of the columns. Thereupon, the static pressure acts upon the bottom of the differential plunger 84 and the top of the pump plunger 10.

15 Since the area of the plunger 84 is greater than the area of the plunger 10, the movable system will be moved upwardly, with the result that a suction stroke of the plunger 10 draws liquid through the inlet check valve 12 into the cylinder 37. The net result of a 20 movement of the plungers 84 and 10 is a drop in columns 1 and 2 because the outward displacement of the plunger 84 is greater than the inward displacement of the plunger 10.

25 The valve shifting mechanism for valve 7 preferably is arranged to provide a snap action so that the piston 3 will be moved to a position where a complete throw of the valve from open to closed position, or vice versa, is accomplished. In the device of Figures 30 19 to 24, inclusive, I have shown an embodiment of the invention in which a snap actuating mechanism of this character has been indicated. The particular type of snap valve actuating mechanism which is to be 35 employed may be varied widely, but preferably a system of spring actuation is employed wherein the piston must be moved to a definite position and the spring must be compressed before the valve is released for 40 actuation by the spring. Such a mechanism in pumps is disclosed in the patent to Perry, #933,200, and I contemplate the employment of a snap actuating mechanism of that character in the actual construction of my 45 pump.

5 In the form illustrated in Figs. 19 to 24 I have shown the differential plunger 5 as disposed between the power piston 3 and the pumping plunger 10. The power piston comprises a hollow tubular member fitting in the cylinder member 115, this member preferably comprising a steel forging having passageways 116 communicating with the column 2. The cylinder member 115 has a 5 ground cylindrical bore 117, in which the ground tubular piston 3 fits closely. The cylinder block 115 is connected to the external drop pipe 118 through a reducing coupling 119 and an intermediate coupling member 120, these parts being threaded together. Intermediate coupling member 120 holds a cylinder head member 121 against the end of the cylinder block 115 and provides an upwardly extending tubular flange 10 or collar 122 containing drain passageways

such as 123 shown in dotted lines. Leading 70 from the top face of the collar 122 downward and outwardly to the outside of the coupling 120 the inner drop pipe 124 which encloses the column 1 is connected to a co-operating coupling member 125 which has a telescoping flange 126 embracing the collar 122 and which has a shoulder 127 closing off the upper end of the drain passageways 123.

75 By raising the drop pipe 124 and separating the flange 126 from collar 122 the drain passageways 124 are opened to permit draining of both columns 1 and 2. The cylinder head member 121 has passageways 128 registering with the passageways 116 in the cylinder block 115.

80 The cylinder block is preferably formed with flutes and lands, as previously explained in connection with Fig. 6, forced into a piece of seamless tubing 129. The tubing and cylinder block are mechanically integral though 85 made of separate parts.

85 The section of tubing 129 is threaded into the coupling member 120 at its upper end, and at its lower end is threaded to another piece of seamless tubing 130 which contains a thin tubular liner 131 for supporting the operating stops for the movable member of the switching valve 7. head 144, and to it are connected the rods 145, 145. The lower ends of these rods are connected to a crosshead 146 and to the upper side of the crosshead 146 there is connected a differential plunger 147 which fits within the bore 148 of a cylinder member 149. The cylinder member 149 has flutes and lands permitting the cylinder member to be forced into and held by the shell 150 of seamless tubing.

10 The liner 131 is placed in a counterbore in the shell 150 at the part which extends above the cylinder block 149. The bore 148 communicates by way of a passageway 151 with the outside of the pump through a check 15 valve 152 which opens outwardly.

A tubular shell 153 is connected by threads to the shell 150, and it provides an open space 164 which communicates through the passageway 155 about the cylinder block 149 20 with the open space 156 above the cylinder block 149 and normally in communication with the column 2.

The pumping plunger 10 fits within the bore 157 of the cylinder block 158, and it is 25 connected through the valve cage 159 to the crosshead 146. The valve cage 159 contains a check valve 160. The cylinder 158 has a tapered shoulder 161 at its upper end for scraping off scale, sand and the like when 30 the pump is put into operation and the upper end of said cylinder 158 is held in proper alinement by a spider 162 clamped between the shell 153 and tubular shell 163.

The spider 162 is shown in section in Fig. 23, and it has openings or passageways 35 through which scale, sand and the like can settle into the pocket 164 formed between the shell 163 and the sides of the cylinder 158. The lower end of the cylinder 158 comprises a solid head member 165 held in place 40 in a counterbore in the lower end of the shell 163 by a coupling member 166 which embraces also the flange on the upper end of a valve housing 167 for housing an inlet check 45 valve 168. The inlet check valve 168 is held in a removable cage 169 which provides a suitable seat 170 for the valve. An intake pipe 171 leads to the well through a suitable strainer member 172, as is well understood by 50 those skilled in the art.

The liner 131 within the shell 150 carries two blocks 175 and 176 fastened thereto by suitable screws or the like, and these blocks provide supports for valve tripping members 55 177 and 178. The block 177 is mounted on the stationary blocks 175 through the intermediary of a pair of springs 179. In a similar manner the trip block 178 is guided on a pair of pins 180 with a spring 181 disposed 60 about each of the guiding pins 130 in order to provide a yielding support for the trip block 178. The stem 133 of the valve 7 has a bevel pinion 182 secured thereto. The bevelled gear sector 183 is mounted on a horizontal axis as by means of a pin 184, the pin being

mounted in the arms of the yoke member 141. The bevelled gear sector 183 has rigid therewith an arm 185 which projects out into the path of the tripping blocks 177 and 178. The arm 185 is disposed on a diameter so that its engagement with the blocks 177 and 178 will not tend to rotate the movable system.

The operation of the device is as follows: Assume that the parts are in the position shown, and the columns 1 and 2 exert their pressure within the space 156 and the space 154. The power piston 3 has been opened by the switching valve 7, hydrostatic pressure is exerted equally per unit area on the pumping plunger 10 and the differential plunger 147. The pumping plunger 10 is of a smaller diameter than the differential plunger 5, with the result that the system moves upwardly, taking in liquid below the pumping plunger 10 and moving the movable system upwardly until the arm 185 of the valve shifting mechanism engages the tripping block 177, whereupon the valve 7 will be closed. The next impulse of pressure in the column 1 then drives the piston 3 and connected parts downwardly, opening the discharge check valve 160 of the pumping plunger 10 and transferring liquid from the inside of the plunger 10 to the space 154, displacing by a downward movement of piston 3 and plunger 5 liquid up through the discharge column 2.

When the moving system approaches the bottom of its stroke the trip arm 185 engages the tripping block 178 and compresses the spring 181. The tripping block 178 and also the tripping block 177 are supported on two springs and are formed of arcuate shape, as indicated in Fig. 24. The block 178 may be moved down to a point where the spring is sufficiently compressed to overcome the friction of the valve and connected parts, and thereupon the valve starts to open and the recoil of the spring 181 throws the valve to completely open position. Thereupon the pressures on opposite sides of the valve are equalized and the return stroke of the moving system begins.

This invention secures a highly advantageous result in providing increased speed of operation of the pump, i. e., this pump can make more strokes per minute than the pumps of the class shown in my prior applications. The reason for this is the fact that the motion of the long columns of liquid need not be reversed at each stroke. The inertia of the long liquid columns is great and requires time to stop and start. In the present pump, while separate strokes are made, the columns always move in the same direction. If the strokes of pump and pulsator do not coincide, no harm results, as the succeeding stroke of the pulsator will drive the motor piston to the limit of its stroke

and open the by-pass to prepare it for the return stroke.

I do not intend to be limited to the details of construction which I have illustrated and described, as they obviously may be varied without departing from the invention. I believe it is broadly new to provide a construction in which the two columns are equalized at the end of the stroke and the return stroke of the movable system made by static pressure only. I believe it is broadly new to employ unidirectional pulsations of pressure in a single liquid column for operating a pump.

15 I claim:

1. The method of raising liquid from a depth which comprises, sustaining a pair of hydraulic columns upon opposite sides of a movable member, exposing a part of said member to pressure inferior to the static head of said columns, applying pressure to one of said columns to move said member and to discharge liquid from the other column, then connecting the columns to equalize pressure upon opposite sides of the member, then returning the member by static pressure of the columns applied over a portion of the member opposite the area exposed to the inferior pressure and by one of said movements 30 of the member introducing liquid into the hydraulic system.

2. The method of actuating the power member of a deep well pump, which comprises sustaining a pair of hydraulic columns upon opposite sides of the member, exposing a part of said member to a pressure inferior to the static head of said column, applying pressure to one of said columns to move the member and to discharge liquid 40 from the other column, then connecting the columns to equalize the hydrostatic pressure upon opposite sides of the member, and then moving the member in the opposite direction by static pressure of the columns applied over a portion of the member opposite the area exposed to the inferior pressure.

3. The method of raising liquid by a motor piston disposed between the lower ends of a pair of hydraulic columns and having a larger surface area exposed to one of the columns than to the other column, which comprises moving the piston in one direction by applying pressure to one of the columns, discharging liquid thereby from the other column, equalizing the pressure of the columns by opening them into each other at the piston, then allowing both columns to drop and moving the piston back by the differential reaction of said columns on the piston, and by 55 one of the movements of said piston introducing liquid into one of the columns.

4. The method of operating a deep well motor piston disposed between the lower ends of a pair of hydraulic columns and having a larger surface area exposed to one of the

columns than to the other, which comprises moving the piston in one direction by applying pressure to one of the columns, simultaneously discharging liquid thereby from the other column, equalizing the pressure of the columns on opposite sides of the piston, and moving the piston back by the differential reaction of said columns on the piston allowing both columns to drop.

5. The method of making the return stroke of a motor piston disposed between two hydraulic columns and having a larger surface area exposed to one column than to the other column, which comprises applying pressure to one of the columns opening a 70 passageway from one column to the other about the piston, then allowing liquid from both columns to move by hydrostatic pressure, and by the differential reaction of said columns on the piston returning the piston, 75 and closing off the connection between the columns.

6. A deep well pump comprising the combination of a pumping cylinder having a piston, a pair of liquid columns of substantially 80 equal hydrostatic head extending to said cylinder, means actuated by application of pressure to one of the columns for making a stroke of the pumping piston in one direction, and means actuated by the difference in 85 pressure between the hydrostatic head of the columns and external pressure for making the return stroke of the pumping piston.

7. In combination, a pump having a plunger, a power piston for moving the plunger in 100 one direction, a static head plunger for moving the pump plunger in the opposite direction, and a hydraulic column applying pressure to both plungers, said static head plunger being exposed on one side to a pressure inferior to the static head of the hydraulic column.

8. In combination, means for maintaining a pair of hydraulic columns, a cylinder connected between the lower ends of the columns, a piston in the cylinder, the opposite exposed sides of the piston being of different areas, a bypass for equalizing pressures on opposite sides of the piston and a valve controlling the bypass, said valve being actuated at the ends of the stroke of the piston for alternately opening and closing the bypass.

9. In combination, a cylinder, hydraulic columns connected to the opposite ends of the cylinder, means for applying pressure to one of the columns, a differential piston having one portion thereof fitting in said cylinder and having a portion exposed to an inferior pressure, and bypass means operated at the 120 end of the stroke of the piston for alternately opening and closing the bypass about said piston between said columns.

10. In combination, a cylinder, a piston therein, a discharge hydraulic column con- 125

- 5 nected to one end of the cylinder, a power column connected to the other end of the cylinder, a pulsator for periodically applying pressure to the power column, a plunger connected to the piston and exposed to pressure inferior to the pressure of the hydraulic columns, a bypass about the piston, and means for opening the bypass at the end of one stroke of the piston.

10 11. In combination, a cylinder containing a power piston, a hydraulic discharge column connected to the cylinder on one side of the piston, a hydraulic power column connected to the cylinder on the opposite side of the piston, means for applying pressure periodically to the power column, a static plunger exposed on one side to a pressure inferior to the hydrostatic head of said columns, a by-pass about the piston opened at the end of a stroke 15 in one direction and closed at the end of a stroke in the opposite direction, a pumping cylinder having a plunger connected to the power piston, and inlet and discharge check valves for discharging liquid into one of said 20 columns.

25 12. In combination, a working cylinder having a working piston, a discharge column connected to the cylinder on one side of the piston, a hydraulic power column connected to the cylinder at the opposite sides of the working piston, a pulsator for periodically discharging liquid at high pressure into the power column, a static plunger connected to the working piston, a bypass about the working piston for equalizing the pressure on opposite sides of the same when it is open, a 30 valve for controlling said bypass, and means to open the valve when the working piston has been moved to the end of its stroke by liquid forced down through the power column 35 by the pulsator.

40 13. In combination, a working cylinder having a working piston, a discharge column connected to the cylinder on one side of the piston, a hydraulic power column connected to the cylinder at the opposite sides of the working piston, a pulsator for periodically discharging liquid at high pressure into the power column, a static plunger connected to the working piston, a bypass about the working piston for equalizing the pressure on opposite sides of the same when it is open, a 45 valve for controlling said bypass, and means to open the valve when the working piston has been moved to the end of its stroke by liquid forced down through the power column 50 by the pulsator, said working piston when the bypass is open being moved on the return stroke by a static pressure of one of the columns operating on the static plunger, and means to close said valve when the working piston has been moved to the end of its 55 return stroke.

60 14. In combination, a working cylinder having a working piston, a discharge column 65 connected to the cylinder on one side of the piston, a working hydraulic column connected to the cylinder on the opposite side of the working piston, a pulsator for periodically discharging liquid at high pressure into the working column, a static plunger exposed on one side to the static head of the hydraulic columns and on the other to an inferior pressure, a pump having a pumping plunger for pumping liquid through the discharge column, said plungers being connected axially in line and moved in one direction by the fluid pressure of the power column and moved in the opposite direction by the static pressure operating on said static plunger. 70

75 15. In combination, a pair of liquid columns, a movable piston separating said columns, means for interconnecting the columns about the piston at one end of its stroke, a pump operated by movement of said piston, said pump discharging liquid through one of said columns, and a plunger operated by static pressure of the columns for making the return stroke of the piston and closing 80 said bypass.

85 16. In a deep well pump, the combination of means for holding a pair of hydraulic columns, a movable piston separating said columns, means for opening an interconnection between said columns when the piston has moved to one end of its stroke, means for closing the interconnection on the end of the return stroke of the piston, and means comprising a plunger exposed on one side to static pressure of the columns and to an inferior pressure on the other side for making the return stroke of the piston. 90

95 17. In combination, means for defining a pair of hydraulic columns, a movable power piston separating said columns and moved by pressure difference between the columns, means for periodically discharging liquid under pressure into one of the columns, means for opening an interconnection about the piston at the end of its outward stroke, a connected single acting pump plunger for discharging liquid into the other of said columns, a connected static plunger displaced by movement of said power piston during its outward stroke, said static plunger moving the power piston and the pump plunger to make the return stroke when the interconnection is opened, and means to close said interconnection at the end of said return stroke. 100

105 18. In combination, a working cylinder, a pumping cylinder and a static head cylinder connected in alinement, a pair of hydraulic columns connected to opposite ends of the working cylinder, a connection between one end of the static head cylinder and the discharge column, the other end of the static head cylinder being connected to an inferior pressure, an inlet check valve for the pumping cylinder, a discharge check 110

valve for the pumping cylinder opening into the discharge column, said cylinders having pistons connected together for power movement, and a switching valve for interconnecting the columns about the working piston at the end of its discharge stroke.

19. In combination, a working cylinder, a pumping cylinder and a static head cylinder, all disposed in alignment, pistons for said cylinders connected together in alignment, a pair of hydraulic columns connected to opposite ends of the working cylinder, one of said columns being a discharge column and being connected to one end of the static head cylinder and also connected to receive liquid from the pumping cylinder, and a rotary bypass valve carried by the working piston and adapted to be opened at the end of the downward stroke of said connected piston to interconnect said columns.

In witness whereof, I hereunto subscribe my name this 2nd day of May, 1928.

WILBUR N. SQUIRES.

valve for the pumping cylinder opening into the discharge column, said cylinders having pistons connected together for power movement, and a switching valve for interconnecting the columns about the working piston at the end of its discharge stroke.

19. In combination, a working cylinder, a pumping cylinder and a static head cylinder, all disposed in alinement, pistons for said cylinders connected together in alinement, a pair of hydraulic columns connected to opposite ends of the working cylinder, one of said columns being a discharge column and being connected to one end of the static head cylinder and also connected to receive liquid from the pumping cylinder, and a rotary bypass valve carried by the working piston and adapted to be opened at the end of the downward stroke of said connected piston to interconnect said columns.

In witness whereof, I hereunto subscribe my name this 2nd day of May, 1928.

CERTIFICATE OF CORRECTION.

Patent No. 1,832,667.

Granted November 17, 1931, to

WILBUR N. SQUIRES.

It is hereby certified that error appears in the printed specification of the above numbered patent requiring correction as follows: Page 9, lines 72 to 74, claim 4, strike out the words "and moving the piston back by the differential reaction of said columns on the piston allowing both columns to drop" and insert instead and then allowing both columns to drop and moving the piston back by the differential reaction of said columns on the piston; and that the said Letters Patent should be read with this correction therein that the same may conform to the record of the case in the Patent Office.

Signed and sealed this 9th day of February, A. D. 1932.

(Seal)

M. J. Moore,
Acting Commissioner of Patents.

Granted November 17, 1931, to

WILBUR N. SQUIRES.

It is hereby certified that error appears in the printed specification of the above numbered patent requiring correction as follows: Page 9, lines 72 to 74, claim 4, strike out the words "and moving the piston back by the differential reaction of said columns on the piston allowing both columns to drop" and insert instead and then allowing both columns to drop and moving the piston back by the differential reaction of said columns on the piston; and that the said Letters Patent should be read with this correction therein that the same may conform to the record of the case in the Patent Office.

Signed and sealed this 9th day of February, A. D. 1932.

(Seal)

M. J. Moore,
Acting Commissioner of Patents.
